STEEL ROOF CONSTRUCTION

Robert J. Beeson, Chicago, Ill., assignor to Mather
Humane Stock Transportation Co., a corpora-
tion of Illinois

Application June 9, 1941, Serial No. 397,307

2 Claims. (Cl. 108—5.4)

This invention relates to improvements in steel roof construction.

In the case of freight cars having steel roofs as constructed heretofore in railway box cars or refrigerator cars, for example, the metal sheets of which the roofs are comprised extend transversely over the steel frame of the car from one side to the other. In some cases these metal sheets have been arranged to overlap each other at the sides or edges and have been pressed upwardly and riveted together at these overlying margins to provide a tight joint. In other cases the adjacent edges of the sheets are bent upwardly to form vertical flanges which are confined within an inverted channel member and riveted thereto. In other cases the adjacent margins of the sheets are bent downwardly to fit into a U-shaped cross member or carlin and wedged within the same, being positively locked in place by lugs which pass through openings in said margins and in said carlin.

Various other constructions have been employed, all intended to provide a dust-tight, waterproof joint. In all of said prior constructions, however, it has been necessary to perforate the sheet metal in order to rivet some of the parts to others, and with long continued use such joints do not remain water-tight and have certain other inherent disadvantages.

The general object of my invention is to provide an improved steel roof construction in which the metal sheets may be positioned on the metal frame with the edges of said sheets in the same plane and in abutting relation to each other and welded to each other and to the frame beneath, to provide a seamless, waterproof joint.

Another object of the invention is to provide a rigid roof construction in which the metal sheets are integrally united to each other without the use of rivets or other auxiliary fastening devices which necessitate openings in said sheets.

Other objects and advantages will be apparent from the description hereinafter given of the preferred embodiment of the invention.

In the accompanying drawing—

Fig. 1 is a fragmentary top plan view of a car roof embodying the invention;

Fig. 2 is a section on the line 2—2 of Fig. 1;

Fig. 3 is a side elevation of the structure of Fig. 1.

The frame of the car, which in this case may be assumed to be a box car or a refrigerator car, comprises upright members 10 sometimes referred to as side posts or door posts. These ver-

tical posts are arranged, usually in a row on each side of the car, and have their tops connected by a longitudinal member on each side, composed of an inside and outside Z-bar 11 and 12 respectively, having their upper flanges riveted together and their lower flanges forming a channel member, the inner flange being riveted at 13 to the upper ends of said posts. The outer flange constitutes merely a depending member overlying the side wall (not shown) of the car. These longitudinal members are known in practice as side plates.

These side plates support the transverse metal members 14, known as carlins, which in this instance consist of T-bars bent at the middle, at a slight angle, to provide the desired sloping roof construction. The outer end of each carlin is suitably secured to a so called side plate casting 15, as for example by means of rivets, said casting being riveted also to the composite side plates 11, 12. As shown in Fig. 1, every other carlin is preferably secured to said side plates immediately above one of the upright members, the remaining carlins being supported at an intermediate position preferably half way between the adjacent vertical posts.

The metal sheets 16 which compose the roof are of a length sufficient to extend from one side of the car to the other and of a width equal to twice the distance between the evenly spaced carlins 14, 14, as shown in Fig. 1. The edges or margins of the adjacent sheets rest on the same carlin, the upper surfaces of said sheets being substantially flush with each other, as shown in Fig. 3. The small gap or crack between the edges is then filled with fused metal, preferably by a welding operation as for example arc welding or gas welding, which not only fuses the edges of the two sheets to the carlin but also fuses them to each other, forming an integral structure or watertight seam 17.

The ends of each sheet, i. e., the margins which extend slightly beyond the sides of the car, are bent down before installation to provide substantially vertical flanges 18, which flanges are riveted to said side plates, as shown at 19. The lower margins of said flanges are bent outwardly at 20, in the preliminary forming operation, as shown best in Fig. 2.

Said metal sheets 16 are also welded to the remaining or alternate carlins at a few points along lines transverse with respect to the roof, as shown at 21, 21 in Fig. 1. Such welding fuses the under side of the sheet to the top of the carlin

after the manner of spot welding. Thus each sheet is welded not only at its parallel edges but also at intervals along an intermediate line parallel to said edges.

The construction thus described provides a very rigid roof which holds the car in alignment, as distinguished from prior constructions in which the roof is somewhat flexible and will distort more or less due to the unusual stresses applied during service. This improved, rigid construction is attained without use of auxiliary fastening devices such as rivets and without the necessity of drilling holes in any of the horizontal or substantially horizontal parts of the metal sheets, the only rivets used being those at the sides of the car where the necessary rivet holes are made in the vertical flanges 18. This construction insures against the development of leakage in the sloping roof of the car.

In order to provide for the conventional runway or parallel boards or planks at the peak of the roof or elsewhere, a series of metal saddles 22 are welded to the roof at the desired intervals, as shown in Fig. 1 and the boards 23, which form the runway, are held in place by saddle bolts 24. Thus the addition of these welded saddles does not interfere with the weatherproof construction of the roof as a whole.

Although a specific embodiment of the invention has been illustrated and described, the same is to be considered in an illustrative and not in a limiting sense, as various modifications may be made in the form and arrangement of the parts and certain features may be used without others, all without departing from the spirit and scope of the invention.

I claim:

1. A freight car roof comprising a pair of side plate Z-bars arranged to present a downwardly opening channel therebetween and having ad-

jacent vertical flanges riveted together, a series of castings riveted to said flanges at intervals, a series of spaced T-bar carlins riveted at each end to one of said castings and extending transversely from one of said side plates to the other, and metal sheets having a length greater than the distance between said side plates and having a width equal to a multiple of the distance between centers of said T-bars, each sheet being supported by a plurality of said T-bars with one edge resting on one of said T-bars flush with the abutting edge of the next sheet and welded to said T-bar immediately beneath said edges, the ends of said sheets each being formed as a depending flange and riveted to said vertical Z-bar flanges with the lower edges of said flanges adjacent the upper surface of the outer of the two Z-bars.

2. A freight car roof comprising a pair of side plate Z-bars arranged to present a downwardly opening channel therebetween and having adjacent vertical flanges riveted together, a series of castings riveted to said flanges at intervals, a series of spaced, transverse roof supporting members riveted at each end to one of said castings, and metal sheets having a length greater than the distance between the side plates and having a width equal to a multiple of the distance between centers of said supporting members, whereby each sheet may have its opposite edges resting on said supporting members with its intermediate portion resting on an intervening transverse supporting member, said edges being flush with the abutting edge of the next sheet and welded to said transverse member immediately beneath said edges, the ends of said sheets each being formed as a depending flange overlying and riveted to said vertical Z-bar flanges.

ROBERT J. BEESON.
